JEWELRY DISPLAY CARTON

Russell I. Cuyler, Lyons, N.Y., assignor to Sarah Coventry, Inc., Newark, N.Y., a corporation of New York

Filed Aug. 26, 1960, Ser. No. 61,897

Term of patent 7 years

(Cl. D58—12.7)

FIG. 1 is a perspective view of a jewelry display carton showing the front, top and one end thereof, embodying my new design; and

FIG. 2 is a perspective view thereof, showing the rear, bottom and the same end as shown in FIG. 1; the end not shown is the same as the end shown.

I claim:

The ornamental design for a jewelry display carton, substantially as shown and described.
